UNITED STATES PATENT OFFICE.

OTTO HESSER, OF CANNSTADT, GERMANY.

PAPER-BAG MACHINE.

SPECIFICATION forming part of Letters Patent No. 643,843, dated February 20, 1900.

Application filed May 25, 1896. Serial No. 592,985. (No model.)

To all whom it may concern:

Be it known that I, OTTO HESSER, machine manufacturer, a subject of the King of Würtemberg, residing at Cannstadt, in the Kingdom of Würtemberg, Germany, have invented 5 a certain new and useful Machine for Making Paper Bags and the Like, of which the following is a specification.

My invention relates to improvements in 10 machines for making paper bags and the like.

This invention has for its object to enable 15 paper bags and the like (more particularly paper bags with bottoms) of any suitable form and size to be made on the same machine, also to enable the mandrel, folding-box, longitudinal folder, bottom-folder, and gumming-stamp of the machine to be changed or adjusted according to the form and size of 20 the bag to be made, while the various other parts of the machine may remain for all sizes and forms of bags.

My invention consists in the features, details of construction, and combinations of parts, which will first be described in connection 25 with the accompanying drawings and then particularly pointed out in the claims.

In the drawings, Figure 1 is a plan view of a machine embodying my invention; Fig. 2, a detail plan view showing the driving-shafts 30 and gearing; Fig. 3, a longitudinal sectional view; Fig. 4, a transverse sectional view; Fig. 5, a detail plan view with some of the mechanism removed; Figs. 6, 7, and 8, detail longitudinal sectional, transverse sectional, and plan 35 views, respectively, illustrating the blank-feeding devices; Fig. 9, a detail side elevation illustrating the folding mechanism; Fig. 10, an end view; Fig. 11, a detail side elevation taken from the side opposite that shown in Fig. 9; Figs. 12, 13, and 14, detail views of 40 the folding mechanism; Fig. 15, a transverse sectional view showing particularly the pasting mechanism; Fig. 16, a detail plan view, also showing said pasting mechanism; Figs. 45 17 to 24, inclusive, diagrammatic views illustrating the steps of procedure in folding the bag; Fig. 25, an enlarged detail view showing the manner of discharging the completed bag; Fig. 26, a detail view of the means for 50 driving the gumming-roller; Figs. 27 and 28, detail views of the gum-applying stamps and their attached parts; Fig. 29, a detail view

showing the manner of securing the table C to the bed-plate A; Figs. 30 and 31, detail views of the mandrel and its adjacent parts; 55 and Fig. 32 shows two views of the cam mechanism for vibrating the lever F², which moves the stamps into and out of position. Fig. 33 is an enlarged side view showing modifications in the arrangement of the bottom-folders. Fig. 34 is a vertical part sectional elevation thereof, taken substantially at right angles. Fig. 35 is a similar view to Fig. 33, taken from the opposite side; and Fig. 36 is a plan view of Fig. 35. 60 65

The paper blanks Z, (see Fig. 1,) which have been previously stamped out into a suitable form, are placed on a carriage B, which has an intermittent reciprocating movement and between the two rails of which there is 70 arranged a fixed table C, fastened on the bed-plate A of the machine. The said table C is secured to the bed-plate A by means of legs c³, which are secured to the table and to the bed-plate A in any suitable manner, as by 75 bolts c⁴, passing upward through the bed-plate A and screwed into the table C, as shown in Fig. 29, the legs c³ being tubular.

In one movement of the carriage B, which is carried by rollers b', Fig. 4, the paper blanks 80 Z are conveyed from the first station I (on which they are placed) onto the first halting-place II, where the sheets are gummed at certain places and retained on the immovable table C by means of a plate d, carried by an 85 oscillating arm D. On the return of the carriage B this plate d holds the sheets fast on the table C until the next forward movement of the carriage, when a fresh blank Z, which has been placed on the first station I, is conveyed 90 to the gumming-station II, while the blanks Z, which have already been gummed, are released by the arm D and conveyed from station II to the next station III, and there again retained on the table C by another similar device d on the return of the carriage. 95 In this manner the paper blank Z is gradually conveyed to stations IV and V. In this latter station the blank Z is folded into a suitable form on the mandrel L and the open 100 sides, as well as the bottom, are stuck down. From station V the finished bag is then pushed (at right angles to the previous course of movement) off the mandrel L and conveyed to the

next station VI, where it is prevented from returning with the ejecting-rod by an elbow-piece placed in front of its open edge, and is subsequently pushed over a beveled block V'.

5 Stations III and IV have no further object than to give time for the gum to dry—i. e., to become viscid.

The operation of the carriage B, as well as of the various operating devices which are necessary for the conversion of the paper blank Z into a bag Z' with a bottom, is effected by means of suitable peculiarly-shaped cams 1 to 15. These are mounted on two parallel shafts A' and A³ and a cross-shaft A², Fig. 2, 15 which three shafts are mounted in bearings or brackets a on the frame under the bed-plate A. The shaft A' is driven by means of a friction device from the belt-disk E³, while the shafts A² and A³ are driven from the shaft 20 A' by means of bevel-gearing a'.

As already mentioned, the table C is fixed stationary on the plate A. The forwarding-catches b are arranged on the carriage B (see Figs. 6 to 8, Sheet 2) and are beveled off at the 25 rear and have recesses in front in which the blanks Z are laid. On the carriage moving forward these catches b carry the blank Z with them and bring it to the next stopping-place. In order that the sheet may not be 30 carried too far on the stopping of the carriage B, elbow-levers C' are arranged beneath the fixed table C, and are each provided at both sides with two small adjustable angle-pieces c, which encounter and retain the blank. These 35 elbow-levers are coupled at their other end with a lever c², Fig. 3, by means of a common rod c', which lever c² is mounted in a bracket C², fixed to the bed-plate A, and receives its movement from the stopping-cam 2, Fig. 3, 40 by means of the rod C³, connected therewith.

The carriage B, which is carried by the rollers b', is connected by means of an elbow-piece B' and link b², pivoted in sockets b' thereon, with an operating-lever B², which is 45 mounted on the rock-shaft a² of the frame and receives an oscillating motion from the cam 1, mounted on the cross-shaft A², by means of the rod B³, connected with it, and transfers this movement to the carriage B. As soon 50 therefore as the carriage B makes a forward movement the elbow-pieces C' are turned so far that the angle-stops c project above the table C and come in contact with the blank Z. The retainer-plate d then immediately presses 55 the blank Z down onto the table C and holds it fast. The elbow-levers C' then turn back again, and the stops c disappear under the table. On the return of the carriage B the catches b, which are beveled or tapered in the 60 rear, slip under the paper blanks Z, which are held down by the retainers, lift these sheets, and then slip away under them. Before the forward movement again takes place the retainer-plates d are raised by means of the arms 65 D and release the blanks Z, and the latter are then on the next forward movement further forwarded to the next stopping-place.

The retainer-arms D are mounted on a common shaft D', Fig. 1, and are operated by means of a lever d', fixed to the latter and rod 70 D², Fig. 15, from a cam 3, which is mounted on the parallel shaft A³, Fig. 15.

The arrangement at the station II, where the sheets are gummed, consists of gumming-stamps H, H', and H², Figs. 15 and 16, adjustably mounted on a plate F⁵, as is obvious from Figs. 27 and 28, which is detachably connected to a sliding piece F, which latter is moved on guide-bars f by means of a rod F', connected to a lever F², which latter receives 80 movement by means of a rod F³ from a cam device 4, which is operated by the shaft A', which cam device consists of a collar 1^a, fixed on the shaft A' and rotating within a link 2^a, secured to the end of the rod F³ and carrying 85 at each end a roller 4^a, said rollers being on opposite sides of the said link 2^a. At each side of the collar 1^a is secured a cam 4^b, these cams being secured to the said collar and to the shaft A'. The periphery of each cam is 90 in contact with its corresponding roller 4^a, whereby as the shaft A' rotates the link 2^a will be reciprocated, so that the sliding piece F is caused to describe a horizontally-reciprocating movement at right angles to the direction of movement of the carriage B. The gumming-stamps H, H', and H² also make this 95 horizontal movement. The guides f of the sliding piece F, to which is attached an operating-rod F', are fixed to a support G, which is vertically adjustable on guide-bars g and which is connected with a rack G', this latter being pivotally connected with a vertically-oscillating lever g'. The latter receives its movement by means of a roller connected 100 thereto and traveling on a cam 5, which is fixed on the parallel shaft A'. 105

If the gumming-stamps H H' H² convey no gum onto the blanks Z, the stamps or rather the vertically-moving support G is not lowered, and this is effected by not releasing a pawl g², which engages in the rack G' and is mounted on a bracket G². A lever G³, Fig. 15, mounted on a projection f⁴ of a bracket F⁴, which carries the lever F², serves for releasing the said pawl g², and for this purpose said lever G³, which is maintained in a given position by means of a spring g⁴, is connected with the pawl g² by means of a connecting-rod g⁵, having a slotted end, through which passes a pin g⁶, carried by the pawl, whereby the pawl is forced to remain constantly engaged with the teeth of the rack G', so that the latter can only descend when the machine attendant places his foot on a treadle at the free end of the lever G³, thus causing the latter to be pressed down and the pawl g² to be disengaged from the rack G', and in this condition it can descend, together with the mechanism connected with it. 110 115 120 125

The gumming-roller e of the gum-holder E is constantly rotated by means of the device shown in Figs. 1 and 26, so that fresh gum is always equally distributed over the surface 130

of the roller. The stamps H H^2 , which rub on the gumming-roller e , are always evenly coated with gum on their stamping-faces, and on the descent of the support G the gum is 5 conveyed onto the parts of the sheet Z which are shown shaded in Fig. 1 of the drawings, (station II.)

The continuous operation of the gumming-roller e is effected by means such as shown in 10 Fig. 26 and consisting of belt-pulleys e^1 e^3 e^4 e^5 from the shaft E' , which through belt-pulleys e^6 and e^7 is operated by means of a friction-pulley e^8 , mounted on the same shaft as the pulley e^1 , which pulley e^8 rests on the driving-belt pulley E^3 of the machine. The shaft of the friction-pulley e^8 is adjustably mounted in a lever E^2 , and the pulley e^8 may be thrown out of operation by elevating the lever E^2 .

The blanks Z pass from station II over stations III and IV (where they are intermittently held down by retainer-plates d) to the 20 station V, where the main functions are completed.

The mechanism operating at station V is 25 mainly shown in Figs. 9 to 14 of Sheet 3 or Figs. 33 to 36 of Sheet 6 of the accompanying drawings. In place of the table C , which ends at this stopping-place, and of the carriage B , which also only travels as far as this stopping-30 place, a vertically-movable folding-box J is provided, Figs. 10 to 14, which box when at rest has its upper part level with the table C , and on this box the blank Z is held in a proper position by contact with two vertical elbow-35 pieces w in place of the elbow-pieces c , previously mentioned. A hollow core or mandrel L lies over the folding-box J , which mandrel is removably fixed in a support K , fixed on the bed-plate A at one side of the machine, 40 as will be fully understood from Figs. 30 and 31. The folding-box J is fixed on a vertical guide-bar i' , which is held in a socket J' , and connected with an operating-lever J^3 by means of a coupling-piece J^2 and a link 45 i^2 . Said lever J^3 is operated by a cam 6 on the shaft A' . An extension of the coupling-piece J^2 , which is guided at the end by a bar i^4 , prevents the folding-box from turning sidewise. The blank Z lies in the position shown in Fig. 17, Sheet 5, on the folding-box J , directly under the folding-mandrel L . On the box J being raised the blank Z looks at from above assumes the form shown in 50 Fig. 18. The blank Z is then folded over the upper surface of the mandrel L by the first longitudinal folder q , which is attached to the folder-carrier Q . The carrier Q , carrying the folder q , (see Figs. 11 and 12,) slides in guides on the support K and is moved 55 over the mandrel L by means of a lever Q' , which is pivotally connected at k to the support K and connected by means of the coupling-rod q' with the carrier Q . The lever Q' receives movement from a lever Q^2 , which is 60 connected with the lever Q' by a link q^2 and which carries at its other end a roller-bearing on a cam 7. The gummed longitudinal side

of the blank Z is now pressed over the already folded-down side (to which it adheres) in a similar manner to that previously described 70 by means of a second longitudinal folder p , which is mounted on a carrier P and operated from a cam 8 by means of link p' , elbow-lever P' , and rod p^2 . In order to firmly press the gummed side, a plate N , Fig. 10, provided with an india-rubber face n , is employed, which by means of an elbow-arm N' , pivotally mounted in projection k' of the support K , is pressed down by means of a rod N^2 from a cam 9 on the longitudinal side of the folded blank Z . In order that the elbow-lever N' shall return automatically to its normal position, in which the plate is elevated, a suitable weight n^2 is provided on the rod N^2 . The blank Z has now the form shown diagrammatically in Fig. 20, looking from above—that is to say, the bottom parts are not yet folded down.

S' S^2 S^3 S^4 are the bottom-folding slides, (shown on a larger scale in Figs. 13 and 14,) 90 which slides are mounted firmly on bars s' to s^4 , which are arranged to slide on the inner side of a support O , and serve for folding around the bottom parts of the bag. The movement of the bottom-folding slides takes place one 95 after the other in the succession I II III IV, (shown in Fig. 14,) the slides S' to S^4 successively rubbing on the end of the mandrel L and effecting the folding down of the bottom parts of the bag Z . Thus two diametrically opposite bottom-folders always rest on the core. The three slides S' S^3 S^4 , or rather their guide-bars s' s^3 s^4 , receive their movement from a common slide-bar O' , (see Figs. 9 and 10,) mounted in projections o on the support O , 105 which slide-bar O' receives a reciprocating motion by means of elbow-lever R , link r , and rod R' from a cam 11. This movement is transferred in different ways to the operating-levers T' T^3 T^4 of the respective bottom-folders, which are revolubly mounted on pivots o' , o^3 , and o^4 . The elbow-lever T' comes first into action and pushes the bottom-folder S' downward. Then folding-slide S^2 is 110 moved by means of a special cam 10 through a lever T^2 , which is pivotally mounted on a support a^3 and is connected by means of a link t^2 with the slide s^2 of the bottom-folder S^2 . The drawing back of the lever T^2 into its normal position is effected by means of a 115 spring t^3 . In its normal position the lever T^2 rests on the set-screw t^4 , Fig. 9. After bottom-folder S^2 there comes into action bottom-folder S^3 by means of a lever T^3 , pivotally mounted on a projection o^3 of the support O , 120 which lever is operated by an arm o^5 , fixed on the slide-bar O' , and finally the bottom-folder S^4 is operated by lever T^4 , pivoted at o^4 , connected to the folders S^4 , and provided at its upper end with a pin which projects 125 into a slot in the slide-bar O' , whereby the latter is first moved back to a certain extent before the slide S^4 comes into action. A spring o^6 , connected at one end to the slide O' and

at the other end to the support O, serves to retract the slide O' after it has been moved by its actuating mechanism from the cam 11. The folding around of the bottom parts of the blank Z, which now forms a bag Z', is thus effected, and there then takes place the further action of the ejection of the bag Z' from the mandrel L under the constant pressure of a stamp against the bottom of the bag, 10 which function may most clearly be seen from Figs. 10 and 13 on Sheet 3.

An ejecting-rod L' is movably mounted in the hollow mandrel L, Fig. 10, and on one end of this rod is attached a small plate l', which 15 passes into the conical front opening of the mandrel L and forms one plane with the end face of the latter. The rod L' is connected by means of a connecting-link l² with the lever L², pivotally mounted on a bracket L⁴, 20 which lever L² receives motion from the ejecting-cam 14 by means of a rod L³. A rod M is arranged in guide-supports M' in a line with the rod L' on the opposite side, and said rod M is provided in front with an india-rubber-covered plate m. Before the rod L' or its 25 plate l' commences the ejection of the bag Z' from the mandrel L the india-rubber face of the plate m presses against the folded bottom of the bag Z'. The rod M is connected by 30 means of a link m' with a lever M², which is pivotally mounted on a bracket M⁴ and operated by means of a rod M³ from a cam 12. A brake-segment m² is fixed onto lever M². A brake-block m³, which is pressed down by 35 means of a spring m⁴, having an adjustable pin m⁶, bears on said brake-segment. The pin m⁶ of the brake-block M³ is adjustably mounted in one end of a lever M⁶, the other end of which carries a roller engaged by a 40 brake-cam 13. The lever M⁶ is pivotally mounted on a standard M⁵, which is attached to the bracket M⁴. The latter is supported from below by means of a support m⁴. So long as the ejection of the bag from the 45 mandrel takes place the india-rubber face of the plate m rests, as already mentioned, against the bottom of the bag Z', and the cam 13 is operated in such a way that it presses the brake-block M³ strongly against the brake-segment 50 m². The pressing back of the rod M by means of the rod L' forms, therefore, a yielding resistance, and the consequence of this is that the bottom of the bag Z', situated between M and L', is powerfully compressed during the 55 ejection of the bag from the mandrel, so that the gum in the bottom parts adheres so firmly that any automatic separation of the gummed bottom is avoided and a thoroughly-smooth bottom is obtained. The rods L' and M, together with the bag Z', having reached the 60 end of the ejecting movement, the rod M, together with the plate m, remains temporarily stationary, while the ejecting-rod L' moves so far back again that its conical plate l' rests 65 in the corresponding recess in the hollow mandrel L.

In order that on the return of the ejecting-

bar L' the bag shall not return with the same, the device shown in Figs. 9, 12, and 25 is employed. This consists of a plate U², on which two elbow-pieces U are adjustably mounted. On one of these elbow-pieces U, as shown in Figs. 25 and 12, there is attached in addition a retaining-arm u. The plate U², 70 together with the elbow-pieces U and arm u, is operated from the cam 15 (see Fig. 9) by means of an arm u', mounted on the lever U', in such a way that the plate U², together with the elbow-piece U and the retaining-arm u, is before the returning movement of the ejecting-bar L' pushed so far against the bag Z' 75 that the arm u rests in front of the end of the bag and prevents its return movement. Before, however, the plate l' of the rod L' reaches the edge of the bag the plate U², together with the arm u, returns so far back 80 that the plate l' can pass by. A second and more powerful pushing of the plate U² against the bag Z', which lies loosely on the block V, then takes place, the elbow-piece U throwing 85 the finished bag Z' over the sloping-shaped block V, from whence it slides into a collecting-receptacle. The lever U' is retained in a suitable position by means of a spring u², and by means of this spring its roller u⁴ is pressed 90 against the cam 15 and operated by the latter.

On each reciprocating movement of the carriage B a fresh sheet is always laid on the first station and a finished bag, with a bottom completed, is ejected. The cams 1 to 15 are so arranged that the actions of the various devices, more particularly those of station V, follow in succession at the right time.

Sheet 5 of the drawings, Figs. 17 to 25, shows the gradual formation of the paper blank Z 105 into a bag with a bottom. Fig. 17 shows the blank Z lying under the mandrel L. In Fig. 18 the folding-box J has pressed the sheet over the mandrel L. In Fig. 19 the first side-folder q has completed one longitudinal fold. 110 In Fig. 20 the second side-folder p has completed the second longitudinal fold. Figs. 21 to 24 show the formation of the bottom after the bottom-folders S' to S⁴ have successively 115 operated. Fig. 25 shows the removal of the finished bag from the mandrel and the ejection of the same.

According to the sectional form of the mandrel L (which may be of a round, oval, rectangular, polygonal, or other form, as desired) the forms of the longitudinal folders q and p must be arranged. A modification of the bottom-folders must be made corresponding to the sizes of the bag by changing the respective folders S' to S⁴.

A device for folding broad bags is shown in Sheet 6 of the drawings. Attention in this case is directed to the fact that the blank which is pushed over the folding-box J on passing the recess i of the folding-box would 120 descend in front and encounter with its front edge one side of the recess i and would bend or could not be brought into the correct position. In order to avoid this, a bridge-piece

X is arranged in the recess i of the folding-box J, lying at the top and level with the upper surface of the folding-box. This bridge-piece is vertically movable, which movement is produced by mounting it on a bar which slides in a socket x' on the folding-box J. A spring x^3 , which is fixed at one end to the socket x' of the folding-box and at the other end to the lower stop-ring x^2 on the guide-bar x , holds the bridge always in the above-mentioned position, while an upper stopping-ring x^4 bears against the socket x' . If the folding-box J be pushed against the mandrel L, the bridge X yields with a spring action and lies then in a suitable depression in the recess i of the folding-box. On the descent of the folding-box the bridge X presses the sheet of paper Z from below against the mandrel L until the bridge again lies level with the upper surface of the folding-box. The folding of the bottom parts in the case of wider bags is also performed in another manner to that hereinbefore described. The succession in which the bottom-folders S' to S⁴ come into action is also different. In this case the horizontal folders S³ and S⁴ first come into action and then the upper folder S' and finally the lower folder S². The corresponding succession in the action of the folders is indicated by I to IV in Fig. 28. The device for operating the bottom-folders is of course suitably modified. The bottom-folders S³ and S⁴ are again operated from a common slide O' by means of levers T⁸ and T⁴, and the lower slide S² is also set in action as before by the lever T². On the other hand, the operation of the bottom-folder S', which is here the third bottom folder which comes into play, is effected in a different manner from that previously described by means of an elbow-lever T⁵, Fig. 26, which is operated by means of a slide-bar t⁵. This slide-bar t⁵ is beveled at the top, and one arm o⁵ of the lever T⁵ is drawn, by means of the spring f⁷, against the bar t⁵ in such a way that the roller r' always rests on the edge of the bar t⁵. The latter is arranged so as to slide in a socket or bearing o⁷ of the support O and is operated from the extended lever T² by means of a link t⁶. On the raising of the slide-bar t⁵ the lever T⁵ is turned, the roller r' being forced outward by the upper inclined edge of the bar. As soon as the roller r' has passed the inclined part of the bar t⁵ and engages the vertical part a further movement of the lever T⁵ can no longer take place, even if the slide-bar t⁵ be moved farther, since there is no tendency of the bar t⁵ to force the shoe outward. The return movement of the lever T⁵ takes place by means of the spring f⁷ after the bar t⁵ has been lowered.

Having thus fully described my invention, what I claim is—

1. In a machine for making paper bags and the like, the combination of a stationary table having openings therein at predetermined distances apart, the spaces between the open-

ings constituting stations to which the blanks are moved in succession, a reciprocating carriage having rails at opposite sides of the table, forwarding-catches for the blanks arranged on the rails, the same being beveled or inclined rearwardly and downwardly, and movable devices for limiting the movement of the blanks operated to pass upwardly through the openings on each forward movement of the carriage.

2. In a machine for making paper bags and the like, the combination of a stationary table having openings therein at predetermined distances apart, the spaces between the openings constituting stations to which the blanks are moved in succession, a reciprocating carriage having rails at opposite sides of the table, forwarding-catches for the blanks arranged on the rails, the same being beveled or inclined rearwardly and downwardly, and pivoted elbow-levers having angle-pieces working upwardly through the openings in the table for limiting the movement of the blanks on the forward movement of the carriage.

3. In a machine for making paper bags and the like, the combination of a stationary table having openings therein at predetermined distances apart, the spaces between the openings constituting stations to which the blanks are moved in succession, a reciprocating carriage having rails at opposite sides of the table, forwarding-catches for the blanks arranged on the rails, the same being beveled or inclined rearwardly and downwardly, elbow-levers pivoted beneath the table and having angle-pieces working upwardly through the openings in the table, means connecting all of said levers, and means for operating the levers simultaneously to elevate the angle-pieces at the forward movement of the carriage.

4. In a machine for making paper bags and the like, the combination of a stationary table having openings therein at predetermined distances apart, the spaces between the openings constituting stations to which the blanks are moved in succession, a reciprocating carriage for the blanks having rails at opposite sides of the table, forwarding-catches for the blanks arranged on the rails, the same being inclined rearwardly and downwardly, means operating upon the blanks to hold them in position on the table at each forward movement of the carriage and pivoted levers beneath the table having angle-pieces working through the openings on the forward movements of the carriage, for limiting the distance to which the blanks are carried.

5. In a machine for making paper bags and the like, the combination of a stationary table, a reciprocating carriage for the blanks, and gumming devices for the blanks, the same consisting of a slide having a horizontally-reciprocating movement at right angles to the movement of the carriage, a plate detachably connected to said slide, guides for the slide

carried by a support having a vertical movement, means for engaging and releasing the support, gumming-stamps adjustably supported by the plate and partaking of the movements of the slide, and foot mechanism for operating the parts, substantially as described.

6. In a machine for making paper bags and the like, the combination of a stationary table, a reciprocating carriage for the blanks, and gumming devices for the blanks, the same consisting of a slide having a horizontally-reciprocating movement at right angles to the movement of the table, a support for the slide, and an operating-rod, said support having a vertical movement, a plate detachably connected to the slide, gumming-stamps adjustably supported by the plate, and partaking of the movements of the slide, a ratchet pendent from the support, a pawl engaging the ratchet and means for releasing the pawl to lower the stamps upon the blanks.

7. In a machine for making paper bags and the like, the combination of a stationary table, a reciprocating carriage for the blanks, and gumming devices for the blanks, the same consisting of an applying-roller, a slide having a horizontally-reciprocating movement at right angles to the movement of the table, a support for the slide having a vertical movement, means for maintaining the support in an elevated position, and for releasing the same to be lowered, a plate detachably connected to the slide, gumming-stamps adjustably supported by the plate, and partaking of the movements of the slide, and foot mechanism for operating the stamps, substantially as described.

8. In a machine for making paper bags and the like, the combination of a stationary table, a reciprocating slide for the blanks, a hollow mandrel located at the end of the table at right angles thereto, and a vertically-movable folder-box, J, working beneath the mandrel, substantially as described.

9. In a machine for making paper bags and the like, the combination of a stationary table, a reciprocating slide for the blanks, a hollow mandrel located at the end of the table at right angles thereto, a vertically-movable folder-box, J, a guide-bar therefor, a coupling uniting the bar to said folder-box, and an operating-lever for moving the parts, substantially as described.

10. In a machine for making paper bags and the like, the combination of a stationary table, a reciprocating slide for the blanks, a hollow mandrel at the end of the table, a reciprocating folder-box beneath the mandrel, a series of longitudinal folders for the blanks, a sliding carrier for the folder, and means for operating the carrier.

11. In a machine for making paper bags and the like, the combination of a stationary table, a reciprocating slide for the blanks, a hollow mandrel at the end of the table, a reciprocating folder-box beneath the mandrel, a

series of longitudinal folders for the blanks, a sliding carrier therefor, a series of folders for the bottom flaps of the bags, a carrier therefor, and means for operating the said carriers.

12. In a machine for making paper bags and the like, the combination with the rods, L', and M, of the ejector devices for the bag, of the lever, M², the brake-segment fixed on said lever, a spring-pressed brake-block bearing on said segment, and the lever, M⁶, all operating substantially as described.

13. In a machine for making paper bags and the like, the combination with a table provided with openings, a reciprocating carriage having rails at each side of the table, and conveying-fingers mounted on said rails, of elbow-levers mounted beneath the table, stops adjustably mounted on said levers and arranged to project through the openings in said table, a rod connected to the elbow-levers, and means for actuating the rod.

14. In a machine for making paper bags or the like, the combination with a guide device, a support movable on said guide device, and paste-applying mechanism carried by said support, of means for reciprocating the paste-applying mechanism in one direction, and means for reciprocating the support at an angle to the direction of movement of the paste-applying mechanism.

15. In a machine for making paper bags or the like, the combination, with a guide device, a support movable thereon, and a second guide device at right angles to the other one and carried by the support, of a paste-applying stamp mounted on the second guide device, means for moving said stamp, and means for moving the support.

16. In a machine for making paper bags and the like, the combination with a support, and paste-applying mechanism carried thereby, of a rod connected to said support and provided with a rack, cam mechanism for reciprocating said rod, a pawl arranged to engage the rack, and means for holding said pawl out of engagement with said rack.

17. In a machine for making paper bags and the like, the combination with a support and paste-applying mechanism carried thereby, of a rod connected to said support and provided with a rack, a lever connected to the end of the rack, a roller carried by the lever, a rotatable cam arranged to bear against the lever, whereby the latter is vibrated, a pawl in engagement with the rack, a rod connected to the pawl, a treadle connected to the rod, and a spring for normally holding the treadle so as to retain the pawl in engagement with the rack.

18. In a machine for making paper bags and the like, the combination with a carriage arranged to transport the blanks, and a folding-box having its upper surface on a level with the carriage and arranged to receive the blanks therefrom, said folding-box having a recess, of a stop on the top of the folding-box to limit the movement of the blanks, a mandrel

located above the folding-box, and means for lifting the folding-box, whereby the mandrel is received in the recess of the folding-box and the blank partly folded.

- 5 19. In a machine for making paper bags and the like, the combination, with a paste-applying roller, of a pivoted lever E^2 a friction-pulley adjustably mounted on said lever, and arranged to bear against the main driving-pulley of the machine, a belt-pulley connected to the friction-pulley, a belt-pulley connected to the paste-applying roller, and belts and pul-

leys intermediate the previously-mentioned belt-pulleys whereby motion is transmitted from the friction-pulley to the paste-applying roller, and the lever is capable of movement about its pivot, substantially as described. 15

In testimony whereof I have signed this specification in the presence of two subscribing witnesses.

OTTO HESSER.
